10 Claims. (Cl. 179—6.3)

1

This invention relates in general to telephone systems and, more specifically, to apparatus in a trunk circuit that is accessible to both pay-stations and regular subscriber's sub-stations for extending a talking circuit to a toll operator.

Although the present invention is adaptable to the common manual cord toll board, it is particularly valuable when used with automatic toll switchboards in which the class of service is not indicated to the operator by any arrangement of trunk connections. According to common practice in automatic telephone systems, a signal known as a paystation tone is applied to a trunk seized by a paystation to indicate to the answering toll operator that special supervision is required for the refunding or the collecting of coins. In the present invention, the refund of the initially deposited coin is controlled automatically. When a calling paystation is connected to the switchboard and the operator answers, the paystation tone is applied to the connecting trunk for an interval, and then the trunk circuit is interrupted while a negative potential is applied to both trunk conductors extending to the calling station to refund the coin and to remove the paystation tone. After the removal of the paystation tone, the operator in order to be heard at the calling station must delay speaking until the operation for refunding the coin has been completed.

Although a call that is routed to the operator through this trunk circuit may originate from a non-coin station, the trunk circuit still operates the same as for a paystation call and a similar delay in speaking is required. If a supervisory tone is not provided in addition to the paystation tone, the toll operator is not able to distinguish a non-coin call that is connected through this trunk circuit from a call that may be completed without delay through a different type trunk circuit; and even when a paystation call is completed through this trunk circuit for refunding the coins automatically, the operator does not know exactly when the talking circuit is completed after the removal of the paystation tone.

An object of the invention is to connect automatically a tick tone circuit to the trunk after a call is received at the toll switchboard to inform the operator that a delay in speaking to the calling station is necessary.

A further object is to remove the tick tone instantly at the conclusion of the interval during which the potential for operating a refund mechanism is applied to the trunk. The removal

2

of the tick tone informs the operator that the talking circuit is completed.

Figures 1 to 4 inclusive arranged together illustrate the present invention. In Figure 1, the block diagrams represent the circuits of an automatic toll switchboard such as that described in detail in Patent 2,361,313 issued to I. Molnar, October 24, 1944. Figures 2 and 3 show in detail a trunk circuit which is associated with the 10 automatic toll switchboard and which is effective on both incoming and outgoing calls to control supervisory circuits and to complete a talking circuit with either a subscriber's sub-station or a paystation at a distant exchange. The block 15 diagrams shown as LS, TR, SR, R and IC in Figure 4 represent detailed circuits of similar designations shown in Patent 1,855,779 issued to Victor S. Tharp, April 26, 1932. TR is a repeater in the main exchange and is effective on local 20 calls. At the distant exchange, selector repeater SR and repeater R cooperate to connect a calling sub-station such as T to a two conductor trunk which terminates in the trunk circuit at the main exchange. Connector IC has access to 25 called sub-stations.

A brief description of the means for applying and removing the tick tone follows. If a call is being placed from the paystation T of Figure 4 to the toll switchboard of Figure 1, a circuit may 30 be established through the trunk circuit illustrated by Figures 2 and 3. Upon answering the call, the operator receives a paystation tone, and a ground is returned over conductor 209 to operate relay 200, which in turn operates relay 210. Responsive to the operation of relay 210, relay 320 operates and at contacts 321 closes a 35 circuit for applying tick tone to the trunk connected to the toll switchboard and at contacts 323 starts the vibration of weighted armature 322. When the amplitude of vibrations become 40 small, slow-operating relay 380 operates to close contacts 381 and 382. At contacts 381 a low resistance circuit is connected across the trunk extending to repeater R of Figure 4 to cause the 45 paystation tone to be removed, and at contacts 382 a circuit is closed for operating relay 390. Slow-operating relay 390 closes circuits to energize slow-operating relays 330 and 395. Relay 395 transfers trunk conductors connected to the 50 paystation from the operator's talking circuit to a negative potential in order to operate the coin refund mechanism at the paystation, and it also closes a circuit shunting contacts 331 of relay 330. This circuit maintains the application of 55 tick tone to the trunk for the duration of the

refunding period after the initial tick tone circuit has been opened by the operation of relay 330. The operation of relay 330 opens the operating circuit of relay 396, and relay 396 releases relay 395. Upon releasing relay 395 reconnects, the talking circuit between the operator and the calling station and removes the tick tone to indicate to the operator that the call may proceed.

To aid in the understanding of the invention, a detailed description of the operation of the trunk circuit shown in Figures 2 and 3 will be given for a call initiated by a paystation or a regular subscriber's sub-station.

When a calling person at sub-station T dials the number which is listed for the toll operator, selector SR and repeater R respond to select an idle two conductor trunk such as 401 and 402. Upon seizing the trunk, a circuit for applying A. C. ringing generator current is completed at repeater R over the following circuit: conductor 401, break contacts 396, contacts 371, upper winding of repeating coil 324, condenser 335, A. C. relay 340, lower winding of the repeating coil, break contacts 397, and conductor 402. Relay 340 operates and at contacts 341 closes an obvious circuit for operating relay 230. Relay 230 at contacts 231 closes its locking circuit including negative battery, winding of slow-operating relay 230, contacts 216, and ground. After a short interval the circuit for applying ringing current is opened and relay 340 releases. At contacts 232 of relay 230 a circuit for biasing relay 350 is closed from ground, right winding of relay 350 to negative battery, and ground is connected to conductor 430 to busy the trunk to incoming selectors of the main exchange; at contacts 233 start lead 207 for the common start and level distributor is grounded; at contacts 234 the operating circuit for relay 340 is closed; and at contacts 235 the call waiting conductor 208 is grounded. Relay 340 operates. At contacts 311 and 312 operating circuits are prepared for controlling supervisory relays required after the call is answered by the operator; at contacts 313 control conductor 206 leading to bank of call selectors is grounded; at contacts 314 a locking circuit is prepared; at contacts 315 control conductor 209 is connected to negative battery through the winding of relay 200 to mark the trunk position in the banks of the answer finder of Figure 1; and at contacts 316 an operating circuit is prepared for relay 320.

In response to the grounding of start lead 207, an answer finder seizes control conductor 209, and talking conductors 217 and 218. If the call originated from a paystation, a circuit is now complete for transmitting paystation tone from the line switch LS of Figure 4 to the answering position of the toll switchboard to inform the operator of the class of call. The circuit from the line switch LS includes trunk conductors 401 and 402, break contacts 396 and 397, contacts 374, right windings of repeating coil 324, and condenser 325. The circuit for the tone current that is induced into the left windings of the repeating coil includes condenser 326 for connecting the windings in series and conductors 217 and 218, for transmitting the tone to the toll switchboard. Ground potential is returned over the control conductor 209 when the operator answers to complete the following circuit for operating relay 200; negative battery, upper winding of relay 200 contacts 332, contacts 345, and ground potential on conductor 209. Upon operating, relay 200 at contacts 261 completes a circuit for

shorting the winding of relay 340 and for connecting condenser 335 in parallel with condenser 325, at contacts 202 closes circuits for operating relay 210 and for energizing the biasing winding of relay 240, and at contacts 203 prepares circuits for relays 330 and 330. Relay 210 at contacts 211 connects ground at another point to control conductor 430, at contacts 212 closes the locking circuit of relay 310, at contacts 213 completes a circuit for operating relay 320, at contacts 215 places a ground on conductor 429 to disconnect the trunk from an incoming selector at the main exchange, and at contacts 216 opens the locking circuit of relay 230. Relay 230 releases to remove ground from the start lead 207, and from the call waiting conductor 208, and opens one of the ground connections for control conductor 430. The circuit for operating relay 320 may be traced from ground, contacts 241, 213, and 316, winding of relay 320 to negative battery. Relay 320 at contacts 321 extends the tick tone circuit to the operator's receiver over the talking conductors 217 and 218 and at contacts 323 closes intermittently the operating circuit of slow-operating relay 381 through the vibrating weighted spring 322. The operation of relay 381 is delayed by the vibrations of spring 322 to provide sufficient time for the operator to recognize the paystation tone. Upon operating, relay 380 at contacts 381 closes a loop circuit for removing paystation tone, and at contacts 382 closes a circuit for energizing slow-operating relay 390. The circuit for removing paystation tone and also for operating relay 350 includes circuits at repeater R as described in the Tharp patent 1,855,779, trunk conductor 401, break contacts 396, contacts 371, upper right winding of repeating coil 324 contacts 384, left winding of relay 350, lower right winding of the repeating coil, break contacts 397, and trunk conductor 402. At contacts 351 of relay 350 an operating circuit is completed for relay 220. Relay 220 at contacts 221 opens a termination bridge circuit, at contacts 222 prepares a circuit for relay 330 and at contacts 223 closes an additional circuit for connecting control conductors 209 directly to the upper winding of relay 200. The circuit for operating relay 390 may be traced from negative battery, winding of relay 390, contacts 334, 382, and 203 to ground. Relay 390 at contacts 391 disconnects the circuit that is provided for manual control of the collecting or refunding operation, at contacts 392 prepares a circuit for automatically controlling the refund of the initially deposited coin, at contacts 393 completes the circuit for energizing slow-operating relay 395, and at contacts 394 completes a circuit for energizing slow-operating relay 330. Upon operating relay 395 at make contacts 396 and 397 connects negative 110 v. potential through indicating lamp 383 and contacts 392 to both conductors 401 and 402 connected to the distant exchange. The negative potential operates the mechanism at the calling paystation for refunding coins in the well-known manner. At contacts 398 of relay 395 a circuit is closed in parallel with contacts 331 to maintain the tick tone on the trunk circuit until the end of the refunding operation; at contacts 399 a locking circuit is completed for relay 220. The operating circuit closed at contacts 394 for relay 330 may be traced from ground, contacts 351, 222, 394, winding of relay 330 to negative battery. Relay 330 at contacts 331 opens the initial circuit for applying tick tone, at contacts 333 closes its lock-

ing circuit which includes contacts 203 and ground, at contacts 334 opens the operating circuit of relay 390, and at contacts 332 opens the initial circuit connecting control conductor 299 to the upper winding of relay 200. Relay 390 releases after an interval. At contacts 392 the negative 110 v. potential is removed from the trunk, at contacts 393 the circuit of relay 395 is opened, and at contacts 394 the operating circuit of relay 330 is opened. Relay 395 releases. At armatures 396 and 397 the trunk conductors 401 and 402 are reconnected to the operator's talking circuit; at contacts 398 the tick tone is removed to inform the operator that the call may proceed; and at contact 399 the locking circuit of relay 220 opened. During the interval that the loop circuit is disconnected from relay 350, relay 350 releases and opens contacts 351. While contacts 351 are open, the operating circuits of relays 220 and 330 are maintained closed at contacts 399.

If the operator wishes to recheck for paystation tone, the check key in the operators position is operated to connect ground to trunk conductor 218, and to connect negative battery through a circuit having one hundred ohms resistance to trunk conductor 217. Although a circuit is completed over conductor 217 for relay 270, it is margined so as to remain unoperated at this time. The circuit for operating relay 240 extends from battery at the toll switchboard over conductor 217, upper left winding of repeating coil 324, contacts 311, contacts 261, upper winding of relay 240, contacts 202, to ground. The current flow in the upper winding of relay 240 is of such direction to aid the current flow in the biasing winding to operate the relay. Relay 240 opens contacts 241 to release relay 320 which releases relay 380. Relay 380 at contacts 381 causes reconnection of the paystation tone by opening a point in the trunk circuit connected to repeater R as described in the Tharp patent. The restoration of the check key releases relay 240 to re-operate first relay 320 and then relay 380. After an interval the closing of contacts 381 removes the paystation tone as previously described.

After receiving the necessary information for completing the call, the operator instructs the calling person to deposit coins. To collect the coins, the operator operates a coin collect key to apply positive 110 v. potential to trunk conductor 217. The circuit from the toll switchboard is completed over conductor 217, upper left winding of repeating coil 324, contacts 311, winding of relay 270, contacts 262, contacts 202, and ground. A circuit completed for the upper winding of relay 240 is ineffective because of the opposition of the lower winding. Relay 270 operates to close contacts 271 for operating relay 260 over the circuit from negative battery, winding of relay 260, contacts 271, contacts 202 to ground. At contacts 263 a circuit is prepared for controlling collection of coins; at contacts 261 the circuit of the upper winding of relay 240 is opened, at contacts 262 a short circuit is removed from across resistor 266 in series with relay 270, and at contacts 265 a circuit is completed for operating relay 395. Relay 395 at make contacts 396 and 397 completes a circuit for applying positive potential from conductor 217, contacts 263, contacts 391, make contact 396 and 397 to trunk conductors 401 and 402 which are connected to the distant station. At contacts 398 a circuit is completed momentarily from the tick tone lead, contacts 398, contacts 321, winding of repeating coil 324, and over conductor 218 to the toll switchboard. After the

applied positive potential operates the mechanism for collecting coins, the operator restores the coil collect key to open the operating circuit of relay 270. Relay 270 restores relay 260 which opens contacts 265 to release relay 395. Relay 395 completes the talking circuit again and the calling subscriber is then connected through the automatic switchboard to the desired sub-station.

Should it be necessary to refund coins manually, the coin refund key is operated to apply negative potential to conductor 217. Relays 270, 260, and 395 operate sequentially as described for collecting coins and now apply negative 110 v. potential to conductors 401 and 402. Relay 240 may also operate to release relays 320 and 380 according to the previous description for rechecking paystation tone, but their operation is ineffective at this time.

If a trunk line is out of order, the OD and check keys at the switchboard are operated to apply negative potential to both conductors 217 and 218. Check relay 240 operates over a previously traced circuit and OD relay 250 operates over the following circuit: negative battery applied to conductor 218, lower left winding of repeating coil 324, contacts 312, contacts 264, contacts 242, the upper winding of relay 250, contacts 202, and ground. Upon operating relay 250 at contacts 251 and 252 connects a trouble tone to trunk conductors 217 and 218, at contacts 253 opens the operating circuit of relay 280, at contacts 254 connects ground to control conductor 206 to busy the trunk to call selectors, at contacts 255 closes a locking circuit to conductor 257, and also at contacts 255 completes a circuit from conductor 257 to light a trouble lamp which is connected to conductor 256. After restoring the OD and check keys, the operator disconnects from the trunk as described subsequently. Relay 250 is maintained operated until its locking circuit, including negative battery, lower winding of relay 250, contacts 255, and conductor 257, is opened at the test panel.

If the call originates from a regular subscriber's station the operation of the trunk circuit is as previously described except that a paystation tone is not transmitted and the operation of the relays for refunding coins performs no useful function. Since a paystation tone is not transmitted, the application of the tick tone is the only means to inform the operator that the call cannot be completed until after relay 395 operates and then releases to remove the tick tone.

In response to the calling person's hanging up after the completion of the conversation, the current flow is reversed in the left winding of relay 350. Relay 350 releases and at contacts 351 opens the operating circuit of relay 220. Relay 220 at contacts 223 removes a shunt from across the lower winding of relay 200 to place its two windings in series in the circuit completed over the control conductor 203. Relay 200 remains operated through its two windings in series but the additional resistance in the circuit restores a marginal relay in the succeeding circuit to inform the operator that the trunk circuit may be released. When the operator disconnects from the trunk, ground is removed from conductor 209 to restore relay 200. Relay 200, at contacts 202 opens the circuit for relays 210 and 240, and at contacts 203 opens the locking circuit of relay 330. Relay 210 at contacts 211 removes ground from control conductor 430 and opens the biasing winding of relay 350, at contacts 212 opens

the locking circuit of relay 340, and at contacts 213 opens the operating circuit of relay 320. Upon releasing, relay 320 at contacts 323 opens the circuit to release relay 380, and relay 380 at contacts 381 opens the loop circuit to release equipment at the distant exchange.

In order to describe more fully the operation of the trunk circuit of Figs. 2 and 3, its operation is given for a call completed through the toll switchboard to subscriber T₁ of Fig. 4. In response to the operator's dialling, the wipers of the step-by-step call selector of Fig. 1 are raised to the bank level in which trunk circuits for the distant exchange of Fig. 4 are accessible. An idle one of the trunk circuits is selected automatically in response to the control wiper of the selector encountering negative battery over the following circuit; bank contact of the selector, control conductor 206, contacts 258, contacts 319, contacts 205, upper winding of relay 200, and negative battery. The selector connects ground potential at the control wiper to control conductor 206 to operate relay 200, and at the line wipers completes a circuit to operate relay 280. Relay 200 at contacts 201 short-circuits the winding of A. C. relay 340, at contacts 202 completes a circuit for operating relay 210 and for biasing relay 240, and at contacts 205 connects the two windings of relay 200 in series by removing the short circuit from the lower winding. Relay 210 at contacts 211 completes a circuit for the biasing winding of relay 350 and connects ground to the control conductor 430 for busying the trunk repeater TR, and at contacts 215 connects ground to conductor 429 for disconnecting the trunk repeater TR from the trunk circuit. The circuit for operating relay 280 may be traced from the call selector bank over trunk conductors 217 and 218, left windings of repeating coil 324, contacts 317 and 318, contacts 301 and 302, contacts 253, and through the upper and lower windings of relay 280 to negative battery and ground respectively. Relay 280 at contacts 281 prepares an impulsing circuit, at contacts 282 closes a circuit for energizing slow-acting relay 370, and at contacts 283 opens a point in an incomplete circuit of relay 360. Relay 370 at contacts 372 connects the trunk circuit of the distant exchange to impulsing contacts 281, at contacts 373 completes the trunk circuit through the left winding of relay 350, and at contacts 374 prepares the operating circuit of slow-acting relay 360.

In response to impulses sent from the toll switch board over conductors 217 and 218, relay 280 pulses. At contacts 281 the impulses are repeated over the loop circuit to repeater R and connector IC, and at contacts 283 the operating circuit of relay 360 is closed intermittently. Relay 360 is maintained operated during each series of impulses and at contacts 361 short-circuits condensers 325 and 331, and winding of relay 350, and a winding of repeating coil 324 to improve the transmission of impulses. The impulsing loop may be traced from negative battery and a winding of an impulsing relay in the incoming connector IC at the distant exchange, conductor 401, break contacts 396, contacts 372, contacts 384, contacts 361, lower right winding of repeating coil 324, break contacts 397, conductor 402, winding of the impulsing relay in connector IC to ground. In response to impulsing, the wipers of connector IC engage the bank contacts corresponding to the line for sub-station T₁, and if the line is idle, ringing current is automatically applied. When the sending of impulses has ended,

negative battery is sent forward from the toll switchboard over the EC conductor 219 to complete a circuit through contacts 305 upper winding of relay 300, and ground to operate relay 300. At contacts 307 a locking circuit is completed from negative battery, lower winding of relay 300, contacts 301, and ground on control conductor 206; at contacts 308 a short circuit is placed across the impulsing contacts; at contacts 301 and 302 the battery feed circuit, including the windings of the relay 280, is disconnected from trunk conductors 217 and 218; at contacts 303 and 304 each of the trunk conductors is connected through circuits having appropriate resistance to ground; at contacts 306 the EC conductor 219 is connected to ground for supervision; and at contacts 308 a circuit is completed to maintain the circuit of relay 350 closed after relay 370 releases. Relay 280 releases, and at contacts 282 opens the operating circuit for relay 370. Upon releasing, relay 370 at contacts 371 and 372 removes the impulsing contacts from the trunk circuit, and at contacts 374 opens the operating circuit of relay 360.

When the called subscriber at sub-station T₁ answers, negative battery and ground are reversed on conductors 401 and 402 to operate relay 350 over a circuit including conductor 401, break contacts 396, contacts 371, upper right winding of repeating coil 324, contacts 398, left winding of relay 350, lower winding of the repeating coil, break contacts 397, and conductor 402. Relay 350 at contacts 351 closes the operating circuit of relay 220. Relay 220 at contacts 221 removes the line termination bridge from across the talking circuit, and at contacts 224 removes ground from EC conductor 219 to notify the operator that the called sub-station has answered.

When the conversation is completed, the called subscriber returns his receiver to its hook to restore the polarity of trunk conductors 401 and 402 to normal. Relay 350 releases and opens the operating circuit of relay 220. Upon releasing, relay 220 reconnects ground to EC conductor 219 to notify the operator that the called subscriber has hung up. When the operator disconnects the trunk connection, the loop circuit is opened and ground is removed from control conductor 206 to release relays 200 and 300. Relay 200 opens the operating circuit of relay 210 and the biasing circuit of relay 240. Relay 210 at contacts 211 opens the biasing circuit of relay 350 and removes ground from conductor 430 to render the trunk circuit selectable, and at contacts 215 removes ground from conductor 429 to reconnect the trunk repeater TR to an incoming selector.

The means for attaining the objects of the invention have been fully described and included in a particular telephone system, but it is understood that departures and various changes may be effected and still be within the spirit and scope of the present invention as defined in the appended claims.

What is claimed is:

1. In a telephone system, paystation lines having coin collecting means associated therewith and non-paystation lines, an operator's position, a trunk circuit, means for extending calls from either paystation lines or non-paystation lines to said position over said trunk circuit, a coin refund controlling circuit in said trunk circuit, means in said trunk circuit for operating said coin refund controlling circuit automatically to refund a coin in response to the operator's answering either type of call, a tick tone source,

means for connecting said tick tone source to said operator's position for an interval of time to warn the operator that an automatic coin operation is taking place.

2. In a telephone system, paystation lines having coin collecting means associated therewith and non-paystation lines, an operator's position, a trunk circuit including a talking circuit, means for extending calls from either paystation lines or non-paystation lines over said talking circuit to said position, a coin refund controlling circuit in said trunk circuit, means in said trunk circuit for operating said refund controlling circuit to automatically refund a deposited coin in response to the operator's answering either type of call, a tick tone source, means for connecting said tick tone source to the answering operator's position for an interval of time to warn the operator that an automatic coin refunding operation is taking place, and said talking circuit disabled during the operate time of said coin refund circuit.

3. In a telephone system, an operator's position, a calling paystation, a trunk having two conductors, means for connecting said paystation to said position over said conductors, a source of paystation tone, means for connecting said source of paystation tone to said conductors to inform the operator of the class of service, a source of tick tone, means responsive to the operator's answering for connecting said source of tick tone to said conductors, the tick tone warning the operator to delay speaking to the calling person until an automatic coin refunding operation is completed, slow-operating means associated with said trunk, said last means responsive to the operator's answering for automatically controlling the refund of coins deposited at said paystation.

4. In a telephone system, an operator's position, a calling paystation having a coin collecting mechanism, a trunk circuit having a talking circuit, a coin refund controlling circuit, and a tick tone circuit, means for connecting said paystation to said position over said talking circuit, a source of paystation tone, means effective prior to the operator's answering for connecting said source of paystation tone to said talking circuit to inform the operator of the class of service, means responsive to the operator's answering for connecting said tick tone circuit to said position, said tick tone circuit transmitting a distinctive tone to the position for warning the answering operator to delay speaking until the operation of said coin controlling circuit is complete, a relay, slow-operating means also responsive to the operator's answering for removing the paystation tone and for momentarily operating said relay, said relay operating to connect said refund controlling circuit to said paystation and to disable said talking circuit, said relay releasing to enable said talking circuit and to disconnect said tick tone circuit from said operator's position to inform the operator that the talking circuit is prepared for speaking.

5. In a telephone system, two exchanges, a two conductor trunk connecting said exchanges, paystations and regular subscriber's sub-stations having lines terminating in one of said exchanges and having access to said trunk, means at said one exchange effective only if a paystation seizes said trunk for applying a paystation tone thereto, an operator's position, a trunk circuit at the other of said exchanges connected to said trunk, means responsive to the seizure of said trunk by one of said paystations or said sub-stations for connecting said position to said trunk circuit, a

tick tone circuit associated with said trunk circuit, means responsive to the operator's answering for connecting said tick tone circuit to said position to inform the operator that a delay in speaking to the calling person is necessary until subsequent switching operations have been completed, a slow-operating means also responsive to the operator's answering for removing paystation tone, a refund potential, a slow-operating relay momentarily operated in response to operation of said last means, said relay operating to disconnect said trunk from said operator's position and to connect said trunk to said refund potential, the connection to said potential effective if the call was initiated from a paystation to refund coins, the releasing of said relay reconnecting said trunk to said position and disconnecting said tick tone circuit from said position to inform the operator that the call may proceed.

20 6. In a telephone system wherein the talking circuit of a trunk circuit in an established connection from a calling line to an operator's position is completed in response to the operator's answering the trunk call, in combination with 25 time controlled means in said trunk circuit operated a predetermined time after the response of said operator answering said trunk call for automatically disabling said talking circuit, means included in said time controlled means for maintaining said talking circuit disabled for 30 a short interval of time and for thereafter automatically reestablishing said talking circuit, means in said trunk circuit operated in response to the operator's answering the trunk call for 35 transmitting a tick tone to the operator, and means included in said time controlled means for disconnecting said tick tone when said talking circuit is re-established to inform the operator that conversation over the talking circuit may 40 be commenced.

7. In a telephone system wherein the talking circuit of a trunk circuit in an established connection from a calling line to an operator's position is automatically disabled within a predetermined time after the operator answers the trunk call and then is thereafter automatically re-established after a further interval of time, in combination with circuit means for momentarily transmitting a tick tone from said trunk circuit 45 to said operator's position in response to the operator's answering the trunk call, and additional circuit means for continuing transmission of said tick tone until re-establishment of said talking circuit to inform the operator when conversation over the talking circuit may be commenced.

8. In a telephone system, paystation lines having coin collect and refund apparatus associated therewith, an operator's position, a trunk circuit 60 terminating in said position, means responsive to one of said lines calling the operator for connecting the calling line to said trunk circuit and for signalling the operator, a paystation tone source associated with said calling line for generating a paystation tone which is audible to the operator when the operator answers the trunk call, means including a tick tone source associated with said trunk circuit for superimposing a tick tone on said paystation tone in response to the operator's answering, coin refunding circuits 65 in said trunk circuit for effecting a coin refund operation of the apparatus at the calling line, time controlled means in said trunk circuit operated a predetermined time after the operator answers for causing automatic disconnection of

11

said paystation tone from said trunk circuit, refunding means in said trunk circuit for automatically completing said coin refunding circuits to complete the refund operation of the apparatus at said calling line operated in response to the operation of said time controlled means, time delay means operated a predetermined interval after the operation of said refunding means for automatically releasing said refunding means, and means controlled by the release of said refunding means for disconnecting tick tone from said operator's position.

9. In a telephone system, paystation lines having coin collect and refund apparatus associated therewith, an operator's position, a trunk circuit terminating in said position, means responsive to one of said lines calling the operator for connecting the calling line to said trunk circuit and for signalling the operator, a paystation tone source associated with said calling line for generating a paystation tone which is audible to the operator when the operator answers the trunk call, means including a tick tone source associated with said trunk circuit for superimposing a tick tone on said paystation tone in response to the operator's answering, coin refunding cir-

12

cuits in said trunk circuit for effecting a coin refund operation of said apparatus at said calling line, and time-controlled means in said trunk circuit automatically effective a predetermined time after the operator answers for causing the disconnection of the paystation tone, for completing said coin refund circuits to complete a refund operation of said apparatus at the calling line after said predetermined time, and after an interval of time following said predetermined time for disconnecting said tick tone and for disabling said refund circuits.

10. In a telephone system as claimed in claim 9 including a talking circuit in said trunk circuit disabled for talking purposes during the time said refund circuits are effective.
